NUNZIO DAQUINO,
INVENTOR.

BY William A. Hartle,

ATTORNEY.

UNITED STATES PATENT OFFICE.

NUNZIO DAQUINO, OF AKRON, OHIO.

SHOE HEEL.

Application filed September 21, 1923. Serial No. 664,111.

To all whom it may concern:

Be it known that I, NUNZIO DAQUINO, a citizen of the United States of America, residing at Akron, in the county of Summit 5 and State of Ohio, have invented certain new and useful Improvements in Shoe Heels, of which the following is a specification.

The present invention relates to shoe heels, 10 of the detachable or replaceable type, and has for its object the provision of a heel the lower or worn portion of which can readily be replaced or renewed, when same needs renewal or repairs.

15 The invention in hand also aims to provide a heel the lower portion of which can be replaced by a person who is not a mechanic or skilled in the art, the method of replacement being very simple in character, as will be seen as the description proceeds herein.

20 Provision is also made to prevent water entering the heel, as will be described, thereby preventing the rotting of the leather portions of the heel. As a further advantage 25 it will be seen that in the case of the present invention, the bottom of the lowermost lift of the heel need no rasping down, in order to fit on the resilient or rubber portion of the heel since a special frame avoids the 30 necessity of doing this, all of which will be made more clear in the following specification.

In the drawings accompanying this specification, and forming a part hereof, I have 35 illustrated the best mode I have so far devised for the practical application of the principles of my invention.

In the drawings, Figure 1 is a side view 40 of a shoe heel, partly in section, illustrating the use of my invention as applied to a shoe.

Figure 2, is a plan view looking in the direction of the arrows on line 2—2 of Figure 1, the lower or rubber portion of the heel, being removed for the purpose of 45 illustration.

Fig. 3 is a plan view of the rubber lift of the heel taken on line 3—3 of Figure 1.

Figure 4, is a side elevation of Figure 3.

Figure 5, is a side elevation of a specially 50 designed frame used with my invention.

Figure 6, is a front or breast view of the

frame shown in Figure 5, taken from the right thereof.

Figure 7 is a front or breast view of Figure 1, taken from the right of same. 55

Figure 8 is a vertical cross-section of my heel, taken on line 8—8 of Figure 2.

Figure 9 is a front view of a metal guard or plate used with my invention.

Figure 10 is a section on line 10—10 of 60 Figure 9.

Figure 11 is a front or breast view of Figure 1, showing a modified form of front plate used therewith.

In the drawings the numeral 1 indicates 65 a shoe heel, of the ordinary type, and usually of leather or pressed paper, on the bottom of which is placed a frame 2, which may be of leather, hard rubber, celluloid, pressed paper or like material, same being preferably permanently secured by nails or otherwise to the upper portion 1 of the heel, as indicated by the nails 3, 3, etc. It is noted that the portion or frame 2, may be sold in conjunction with the rubber portion 4 of the heel, or the part 2 can be sold with the shoe itself whichever is found to be preferable in trade, and if sold in the latter manner, it is seen that the frame 2 is sold secured to the part 1. The construction of the 70 frame 2 is shown in detail in the Figures 5 and 6 and 2 of the drawings, and consists of a horizontally disposed portion 5, having a depending grooved rim portion 6, and for the purpose of lightening the weight 75 of the frame, the center portion is removed from the frame 2 at 7, leaving the cross bars 8 and 9 as shown clearly in Figure 2. From the Figures 1 and 8 the method of securing the resilient portion 4 of the heel to the 80 frame 2 is clearly shown, the part 4 having preferably a grooved extension 10 which is formed complementary to the groove 11 formed in the frame 2, and adapted to 85 slidably operate therein. It is evident that the rubber lift portion 4 can be engaged with the groove 11 of frame 2, when the lift 4 is advanced from the right as seen in Figure 1 of the drawing. In order to prevent the rubber lift 4 becoming disengaged 90 from the frame 2, I use a preferably metal plate 12, which is bent as shown in Figure

55

100

10 of the drawing, having a downwardly extending flange 13, a horizontally disposed portion 14, and an upwardly disposed flange 15. The portion 13 of the metal plate 12 5 extends across the width of the heel as shown in Figure 7, and at 16, 16 said plate 12 extends upwardly slightly above the top 17 of the rubber lift 4 in order to prevent water entering the interior chamber 18 of 10 the heel, and consequent rotting of the leather or paper portions of the heel. Figure 1 of the drawings shows the metal plate 12 in position, with one flange 15, against the cross-bar 9, and the portion 13 in engagement 15 with the face of the rubber lift 4, from which it is evident the latter cannot become disengaged from the frame 2. It is noted that the rubber lift 4 is preferably cut away at 19, as is also the frame 2 is cut away at 20 to provide an inset for the metal frame 12, so that the metal plate may be flush with the front lifts of the heel, but if desired the slots at 19 and 20 may be omitted, and the 25 plate 12, placed upon the outer surface of the lift 4 and frame 2.

It is further seen that the metal plate 12 in order to hold the rubber lift 4 in position in engagement with the grooved frame 2, is provided with a nail or screw 21, which 30 passes through the rubber lift portion 4, the metal plate 12, cross-bar 9 of frame 2, and embeds itself well into the upper part 1 of the heel. More than one such a screw or nail is deemed unnecessary to accomplish this 35 purpose of securely holding the rubber lift 4 in place, but if found necessary a second nail may be passed through the latter preferably near the rear end of said lift as at point 22. It is evident that while I have 40 shown an angular groove 11 in the frame 2, that any other suitably shaped slot such as rectangular may be used for the purpose.

It is seen further that in placing the metal plate 12 in position that the resiliency of the 45 lift 4 is sufficient to permit the upturned end 15 to be inserted between the rubber lift 4 and the frame 2, as is readily appreciated. In some cases it may be preferable to omit the use of the nail or screw 21, and by extending the metal plate upwardly as 23, Figure 11, and use the small screws 24, 24, to secure the said plate to the frame 2.

From the above description it is seen that I have provided a neat and useful device for 50 the purpose intended, which enables rubber

heels to be added, or replacements made to shoes, by those who are not skilled mechanics, and very expeditiously as well.

I claim:

1. In a shoe heel, a frame having a cross-bar, a resilient lift in slidable engagement with said frame, a recess formed in the vertical breast face of the resilient lift, a metal plate seated in the lift recess, in engagement with the frame cross-bar, and the breast of the resilient lift, and means passing through the resilient lift, the metal plate and the frame, adapted to embed itself into the upper portion of the heel, for securing the resilient lift against slidable disengagement from the frame.

2. In a shoe heel, a frame mounted thereon, a resilient lift slidably mounted on said frame, a metal plate having an upward extension engaging the frame, and a horizontally disposed portion, a downward extension on the metal plate extending across the breast face of the resilient lift, a pair of upward extensions on the metal plate sealing the junction between the resilient lift and the frame, and locking means passing through the resilient lift, the metal plate and the frame, and embedded in the upper portion of the heel, for securing the resilient lift against dislodgement from said metal frame.

3. A metal plate having a rear and upwardly disposed flange, a centrally disposed horizontal portion, and a front portion comprising a downwardly extending flange, and a pair of upward extensions formed thereon.

4. In a shoe heel, a frame mounted thereon, a resilient lift slidably mounted on said frame, a recess formed in the vertical breast face of the resilient lift, a metal plate having an upward extension engaging the frame, and a horizontally disposed portion, a downward extension on the metal plate seated in the resilient lift recess and extending across the breast face of the resilient lift, a pair of upward extensions on the metal plate sealing the junction between the resilient lift and the frame, and locking means passing through the resilient lift, the metal plate and the frame, and adapted to embed itself in the upper portion of the heel, for securing the resilient lift against dislodgement from the metal frame.

In testimony whereof I affix my signature.
NUNZIO DAQUINO.
